UNITED STATES PATENT OFFICE.

DELPHENE H. HAWKINS, OF SPOKANE, WASHINGTON.

BABY JUMPER.

Application filed November 23, 1925. Serial No. 70,901.

My present invention relates to improvements in baby jumpers or children's supports resiliently held for vertical vibration and capable of holding and supporting a child in upright sitting position or of holding the child with its feet touching the floor.

The invention involves the use of a body harness which relieves the child's feet of its weight but permits them to touch the floor. The device is especially designed to support the child's back and also afford a comfortable seat for supporting the child's weight and at the same time afford the required freedom of movement of the child without restrictions in the performance of its usual functions.

Means are provided for bracing the suspending straps to hold them in correct position to properly support the harness or jumper, and the bracing member may readily be detached when required for compact storage arrangements. By the utilization of the device of my invention the parts may quickly and conveniently be assembled and adjusted for use to provide a comfortable device of this character and with equal facility the parts may be unfastened and dismantled when required.

The invention consists in certain novel combinations and arrangements of parts as will hereinafter be more fully set forth and claimed.

In the accompanying drawings I have illustrated one complete example of the physical embodiment of my invention wherein the parts are combined and arranged according to the best mode I have thus far devised for the practical application of the principles of my invention.

Figure 1 is a perspective view of the device as a whole, suspended in proper position and adapted for use.

Figure 2 is a plan view of the body of the harness spread out in flattened position for convenience of illustration.

Figure 3 is a detail at one corner of the rectangular brace for the suspending straps illustrating the manner of connecting the brace with the straps.

Figure 4 is an enlarged transverse sectional view at line 4—4 of Figure 2 showing the seat portion of the harness.

In carrying out my invention I preferably utilize a single-piece body portion 1 of canvas or other suitable material, having ends 2 and 3 and properly fashioned as to shape

to insure a comfortable body harness when the ends 2 and 3 are overlapped at the back to encase the child's body for supporting its hips and back.

A suitable number of short straps 4, here shown as two are secured to the end 2, and complementary buckles 5 are attached to the end 3 by means of which the body portion may be adjusted and fastened together as in Figure 1.

The body portion 1 is fashioned with an angular tubular extension 6 and reinforced by means of interior padding material as 7 which material extends between the two transverse rows of stitches 8 in the extension and affords a padded or cushioned, reinforced seat for the child to straddle.

The seat is detachably fastened to the respective ends 2 and 3 of the harness-body by means of a triangular shaped shield 9 formed integral with the seat and provided at its extreme edge with a number of hooks 10.

The hooks are designed for coupling to selected eyelets 11 on the reinforcing tapes 12 and 13 of the respective ends 2 and 3 of the body harness. By means of the body straps 4 and their buckles the body of the jumper may be adjusted to proper size and position and secured about the body of the child, and by means of the coupling hooks and eyes the seat portion of the jumper may be properly adjusted and fastened to the two ends of the harness body in correct and comfortable position.

Four suspending straps 14, 15, 16 and 17 are preferably fashioned integral with the body-harness of the jumper and spaced at uniformly correct distances apart to properly suspend the harness body.

Each of the suspending straps has a detachable loop-strap 18 with its lower end permanently secured to the suspending strap and its upper end is provided with a detachable fastening device 19. These loop straps are provided for the support of a rectangular brace indicated as a whole by the numeral 20 and they are designed to encase or loop over the corners of the brace in order that when their upper ends are attached to the suspending straps the brace may be held in horizontal position.

The brace holds the four suspending straps in spaced relation and as shown in Figure 3 it is preferably made up of separable bars 21 each having a dovetail mortise

22 and a complementary tenon 23 at opposite ends. The bars are connected together by means of the mortise and tenon joint and each joint is secured by means of a 5 screw 24. The screws are provided with projecting heads 25 and each suspending strap has an eyelet 26 to slip over a screw head. Thus by means of the screw heads and eyelets and the loop-straps 18 the brace 10 is firmly held by the suspending straps to maintain the latter in proper position.

At their upper free ends the suspending straps are passed through a suspending ring 27 supported from a suspending spring 28, 15 which is in turn suspended from an eye-bolt 29 that is anchored to a suitable overhead support.

By means of the buckles 30 the ends of the straps may be uniformly adjusted with 20 relation to the ring to suspend the body harness in correct position. It will be apparent that the child is to be seated with his legs straddling the padded seat and protruding through the side openings afforded 25 by the harness and the body of the harness

encases the body of the child in such manner so as not to interfere with its required freedom of movement while occupying the jumper.

Having thus fully described my invention what I claim as new and desire to secure by Letters Patent is—

In a baby jumper, a harness body comprising a main body portion having overlapping ends, attaching straps and buckles therefor 35 respectively carried by the overlapping ends, a seat extension formed integral with said body and extending from one edge thereof intermediate the ends, eyelet carrying reinforcing strips disposed on the overlapping 40 ends of said body, an attaching shield formed on the free end of said seat extension, and hooks on said shield for engagement with the eyelets of said reinforcing strips when the body ends are in overlapped 45 relation, for covering a portion of the overlap to position the seat extension.

In testimony whereof I affix my signature.

DELPHENE H. HAWKINS.
